UNITED STATES PATENT OFFICE.

GEORGE E. COUTANT, OF DECATUR, ILLINOIS.

UPPER BUFFER ARRANGEMENT FOR RAILWAY CARS.

Application filed August 31, 1923. Serial No. 660,290.

To all whom it may concern:

Be it known that I, GEORGE E. COUTANT, a citizen of the United States, residing at Decatur, in the county of Macon and State of Illinois, have invented certain new and useful Improvements in Upper Buffer Arrangements for Railway Cars, of which the following is a specification.

This invention relates to improvements in
10 railway car vestibules, and more particularly
to the upper buffering devices for the dia-
phragm face plates of such vestibules.

These buffering devices are designed to yieldingly maintain the diaphragm face plates in proper relative position and for restoring them to such position after displacement as the result of the car's passing over curves, crossings and irregularities in the tracks.

20 These buffering devices as now constructed comprise a semi-elliptic spring interposed between the face plate and the end of the car. This spring in service is compressed and expands with corresponding movements 25 of the diaphragm, and in this manner the plates of each pair of diaphragms are maintained in proper position. The opposite ends of the semi-elliptic spring have heretofore only loosely engaged through keepers 30 or the like carried by the end of the car, the spring ends being downturned to prevent displacement thereof. See, for example, patents to Sisson, 1,097,195, May 19, 1914, and Lawler, 1,170,548, of February 8, 35 1916. In service the ends of such springs frequently break off, rendering the device inoperative and necessitating repair or replacement. Another serious objection to this construction is the noise which the free 40 ends of the spring produce in rubbing and knocking against the keepers.

One object of the present invention is to provide an upper buffering device generally similar to those above described but embodying improved features of construction whereby the above mentioned objections are overcome, and, as a result of which, smoother and more noiseless and efficient operation is obtained.

50   Other objects and advantages will be apparent to those skilled in the art from a reading of the following specification, taken in connection with the accompanying drawings, wherein one form of the invention is illustrated.

In the drawings—

Figure 1 is a top plan view of the upper buffer device of the present invention, showing the same operatively mounted;

Figure 2 is a similar view showing the 60 position of the parts upon compression of the spring;

Figure 3 is a front elevation showing the device in operative position on a car;

Figure 4 is a detail view partly in section, showing the mounting of the spring on the rear of the face plate; 65

Figure 5 is a sectional view taken on the line 5—5 of Fig. 4, and

Figure 6 is an enlarged sectional view 70 taken on the line 6—6 of Fig. 1.

Referring more in detail to the drawings, 10 designates the end portion of a car vestibule, 11 the usual bellows diaphragm, and 12 the face plate of said diaphragm. The semi-elliptic spring is shown at 13 and is made up of one or more leaves in the usual manner. Intermediate the ends of the spring 13, preferably at the center thereof, the same is provided with an encircling, two-piece band 14, secured thereto by means of rivets or in any other suitable manner. One piece, 14^a, of this band is of inverted U-shape and fits down over the inner concave surface of the spring, its sides depending over the edges of the leaves thereof and projecting in the form of apertured ears beyond the spring at the opposite side thereof. The other piece, 14^b, of the encircling band is in the form of a plate having a bearing groove 14^c formed therein, this plate being secured against the outer or convex side of the spring in such-wise that the bearing groove 14^c thereof is in alignment with the apertures in the depending ears of the other piece, 14^a. Rivets 95

110
Pending claims of the last page. Projected or otherwise firmly secured to the inner surface of the face plate 12, adjacent the upper edge of the latter, is a bracket 15, also of U-shape in cross-section, its sides projecting rearwardly from the face plate in a direction opposite to that in which the projecting sides of the member 14^a of the band extend. The bracket 15 is of such dimension as to receive between its side walls the apertured ears of the piece 14^a and said side walls are also apertured. A pivot pin 16 extends through the apertures in the sides of bracket 15 and also through those in the depending ears of the piece 14^a and through the bearing groove in the piece 14^c of the

spring-encircling band. In this manner the semi-elliptic spring is securely connected to the face plate, while at the same time being free to oscillate with respect thereto on the pivot pin 16. The pivot pin is headed at one end and adapted to receive a cotter pin or other removable means at its other end, so that the spring may be readily removed at any time should occasion require.

10 Attached to the end portion of the vestibule in the vicinity of the ends of the semi-elliptic spring 13 are a plurality of brackets 17 having projecting side walls 18 apertured near the outer ends for receiving pivot pins 19, also removable to facilitate dismantling. Each end of spring 13 is coiled or looped back upon itself as at 20, these loops each being interiorly provided with steel bushings 21 or the like, through which pivot pins 22 extend. The pivot pins 22 at their outer ends engage suitable apertures in the arms 23 of shackles 24, said arms at their other ends being joined by an elongated bearing sleeve 25 through which the pivot pins 19, previously described, extend. It will thus be apparent that the ends of the semi-elliptic spring 13 are positively connected to the end portion of the car vestibule, the shackles 24 permitting of the ends of the spring moving in an arc back and forth as the spring is compressed and expands. To prevent overthrow and to limit this movement of the ends of the spring, inwardly extending lugs 26 are formed on the sides of the brackets 17, these lugs being so positioned as to engage with the arms 23 of the shackles as the latter move back and forth upon compression or expansion of the spring. The normal position of the spring 40 and its associated parts is shown in Fig. 1 of the drawings, and in Fig. 2 the spring is shown under compression. It will be observed that normally the shackles 24 incline inwardly from the pivot pins 19, resting against the inner sets of lugs 26. Under compression, however, the shackles are rocked outwardly and under maximum compression engage the outer set of lugs 26, as shown in Fig. 2. During this action of the 45 spring and shackles the former is free to rock in either direction on a vertical axis by reason of its pivotal connection to the face plate. Thus the face plate may assume various angular positions without throwing the spring out of alignment or imposing undue strain on either one of the shackle connections.

50 Washers 27 are inserted between adjacent sides of the part 14^a of the spring-encircling band 14 and the upstanding side walls of the bracket 15, when these parts are assembled, and it is also preferred to place washers 28 between the outer ends of the bearing sleeves 25 of the shackles and the adjacent faces of the sides 18 of the brackets 17 when

these parts are assembled. While the use of the washers 27, 28, is preferred, it will, of course, be appreciated that they may be omitted if desired.

It will be obvious to those skilled in the art that the present improvements are susceptible of various changes and modifications without departing from the spirit of the invention, and it is not desired, therefore, to limit or restrict the same to the particular construction or arrangement of parts herein illustrated except where limitations appear in the appended claims.

I claim:

1. The combination with the vestibule and diaphragm face plate of a railway car, of a semi-elliptic spring interposed between said plate and vestibule, and means for limiting the movement of the outer ends of said spring both upon compression and expansion of the latter, said means comprising brackets carried by said vestibule and rockers attached to the ends of said spring and pivotally connected to said brackets.

2. The combination with the vestibule and diaphragm face plate of a railway car, of a semi-elliptic spring interposed between said plate and vestibule, and means for limiting the movement of the outer ends of said spring both upon compression and expansion of the latter, said means comprising shackles pivotally connected to said vestibule and to the ends of said spring respectively.

3. The combination with the vestibule and diaphragm face plate of a railway car, of a semi-elliptic spring interposed between said plate and vestibule, and means for limiting the movement of the outer ends of said spring both upon compression and expansion of the latter, said means comprising shackles pivotally connected to said vestibule and to the ends of said spring respectively, and means for limiting the movement of said shackles.

4. The combination with the vestibule and diaphragm face plate of a railway car, of a semi-elliptic spring interposed between said plate and vestibule, and means for limiting the movement of the outer ends of said spring both upon compression and expansion of the latter, said means comprising brackets carried by said vestibule and rockers attached to the ends of said spring and pivotally connected to said brackets, and means for preventing overthrow of said rockers.

5. The combination with the vestibule and diaphragm face plate of a railway car, of a semi-elliptic spring interposed between said plate and vestibule, and means for limiting the movement of the outer ends of said spring both upon compression and expansion of the latter, said means comprising brackets carried by said vestibule and rockers at-

tached to the ends of said spring and pivotally connected to said brackets, and means for preventing overthrow of said rockers, said last named means being in the form of 5 lugs carried by said brackets.

6. The combination with the vestibule and diaphragm face plate of a railway car, of a semi-elliptic spring interposed between said plate and vestibule and being pivotally 10 connected to both of said elements.

7. The combination with the vestibule and diaphragm face plate of a railway car, of a semi-elliptic spring interposed between said plate and vestibule, said spring being attached at its opposite ends to movable mem- 15

bers carried by said vestibule, and means for limiting the movement of said members in either direction.

8. The combination with the vestibule and diaphragm face plate of a railway car, of a semi-elliptic spring interposed between said plate and vestibule, a transversely grooved plate carried by said spring intermediate its ends, a supporting member mounted on said face plate, and a pivot pin carried by said member and extending through said groove. 20 25

In testimony whereof, I have subscribed my name.

GEORGE E. COUTANT.
